CLAIM

The ornamental design for a combined faceplate for a power receptacle with USB charging socket as shown and described.

DESCRIPTION

FIG. 1 is a front elevational view of a combined faceplate for a power receptacle with USB charging socket showing a first embodiment of my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front, top and left side perspective view thereof;

FIG. 8 is a front elevational view of a combined faceplate for a power receptacle with USB charging socket showing a second embodiment of my new design;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a front, top and left side perspective view thereof.

In the drawings, the broken lines are for the purpose of illustrating portions of the combined faceplate for a power receptacle with USB charging socket that form no part of the claimed design.
